WILLIAM H. H. CLARK, OF BURLINGTON, IOWA.

Letters Patent No. 93,055, dated July 27, 1869.

IMPROVED CAR-COUPLING.

The Schedule referred to in these Letters Patent and making part of the same.

To all whom it may concern:

Be it known that I, WILLIAM H. H. CLARK, of Burlington, in the county of Des Moines, and State of Iowa, have invented a new and improved Car-Coupling; and I do hereby declare that the following is a full, clear, and exact description thereof, which will enable others skilled in the art to make and use the same, reference being had to the accompanying drawing, forming part of this specification.

This invention relates to new and useful improvements in car-couplings, intended to combine the buffers and coupling in one device, capable of automatic attachment, and calculated to provide a very simple, cheap, and efficient arrangement, as hereinafter more fully specified.

Figure 1 represents a plan view of the bottom of two cars provided with my improvements, and coupled together.

Figure 2 represents a partial front elevation of a car having the said improvements.

Figure 3 represents a detail view.

Similar letters of reference indicate corresponding parts.

I form notches A in the sides of the buffer-heads, preferably having right-angular walls at the outer ends a, and curved at the inner ends b of the said notches.

These buffers are connected to the cars, at their inner ends, by springs B, preferring elliptical springs for passenger-cars, and coiled springs for freight-cars.

The said buffers are placed between fixed longitudinal bars C C', which limit the lateral movement of the outer ends of the buffers, which are free to move to a certain extent.

The ends of the buffers are rounded from the corners opposite the notches, and so arranged that when the cars are brought together, the rounded ends will pass each other, allowing the points of each to fall into the notch of the other, and thus become coupled together.

Each buffer is provided with a spring, D, at its side opposite the notches, which springs have a constant tendency to keep the hooks locked together, no matter how much lateral movement the cars may have in either direction.

The longitudinal bars C are curved at their front ends, and the draw-bars or buffers are correspondingly curved, to afford a lateral support to the said draw-bars, as near the ends as possible, and allow them to recede against the springs when the cars run together. The ends of the said buffers strike against the curved walls b of the notches, when they arrest the motion of the cars running together.

For uncoupling these buffers I provide winding-shafts F, with cords or chains attached to them, and arranged to draw them away from each other, and against the springs D.

These winding-shafts may be arranged to be worked either on the platform or the tops of the cars, or on freight-cars, either side of grain on the ground. In the place of the said winding-shafts and chains, levers may be employed, in a manner well understood.

Having thus described my invention,

What I claim as new, and desire to secure by Letters Patent, is—

The draw-bars A, attached to the springs B, when provided with the curved edges in rear of the walls b, in combination with the guide-bar C, having a correspondingly-curved end, the bar C and the spring D, all arranged and operating as described, whereby the draw-bars are permitted greater lateral play at their front ends, as herein described, for the purpose specified.

WILLIAM H. H. CLARK.
